UNITED STATES PATENT OFFICE.

WILLARD A. ELKINS, OF FORT STEVENS, OREGON.

ADJUSTABLE LIGHTER.

1,292,591.

Specification of Letters Patent. Patented Jan. 28, 1919.

Application filed September 7, 1918. Serial No. 253,021.

To all whom it may concern:

Be it known that I, WILLARD A. ELKINS, a citizen of the United States, residing at Fort Stevens, in the county of Clatsop and State of Oregon, have invented certain new and useful Improvements in Adjustable Lighters, of which the following is a specification.

This invention is an adjustable lighter 10 and has special reference to a device for facilitating the lighting of cigars and cigarettes.

One object of this invention is the production of an adjustable lighter which is in 15 the form of a hood movably carried upon a match case, whereby the hood may be moved to an inoperative and out-of-the-way position when not in use although it may be swung to an operative position for allowing 20 the cigar or cigarette to be easily inserted thereinto.

Another object of this invention is the production of an adjustable lighter which is so constructed as to shield the ignited 25 match for lighting the cigar or cigarette from the wind and thus permitting a cigar or cigarette to be easily ignited without accidental extinguishing of the match.

Another object of this invention is the 30 production of an adjustable lighter wherein the hood is provided with a disk for igniting the match although the flame will be protected from the wind and also the light of the match will be shielded to prevent a 35 disclosure or signal means given by the light of the match.

One practical form of construction and assembly of the present invention will be hereinafter described, and is illustrated in 40 the drawing in which—

Figure 1 is a side elevation of the adjustable lighter and match case in use, a portion of the hood being broken away.

Fig. 2 is a side elevation of the device, 45 showing the lighter in inoperative position and fitting upon the casing, and

Fig. 3 is a section taken on the line 3—3 of Fig. 1, the casing being shown in elevation.

One practical form of construction and assembly of the present invention, is disclosed by the preferred embodiment of the device in which the match casing 5 may be 50 of any desired shape, although it is shown as substantially rectangular in cross section

and is elongated as is the general construction of devices of this nature. This casing 5 is provided with a milled surface 6 for allowing matches to be struck thereon if it is not desired to use the adjustable lighter. 60 The closure cap 7 may be carried in any desired manner upon one end of the casing 5, it being intended to have the match extracted from the casing through the end thereof provided with the cap 7. The opposite end of the casing is to be closed to prevent the accidental displacement of matches therefrom although this opposite end is provided with a pocket 8', as indicated in 65 dotted lines in Figs. 1 and 2.

The hood of the adjustable lighter is indicated in general at 8 and comprises a back having side walls 10 extending at right angles thereto and parallel to each other. It will be noted that the side walls 10 are 70 channelled as indicated at 11, the channels extending in alinement with each other and longitudinally of the hood, thus permitting a cigar or cigarette to be easily inserted into the interior of this hood. However, it will be noted that the channel portions are formed at a slight distance from the back, thus forming a passage above the channelled portions, as indicated clearly in Fig. 3 for 75 purposes to be hereinafter set forth. It will be noted that the side walls 10 extend beyond the channelled portions 11 thus forming clamping portions 12 which are out-turned as indicated at 13, thus facilitating the slipping of the hood upon the casing 5.

The journal wall 14 is formed at one end of the hood as indicated in Figs. 1 and 3 and carries a pin 15 upon which the disk 16 is rotatably mounted. This journal wall 14 is slotted as indicated at 17, thus permitting the disk 16 to extend into the interior of the hood and also to extend beyond the outer portions of the hood as clearly 85 shown in the drawings.

This hood 8 is provided with a bearing lug 100 18 formed adjacent the journal wall 14 and projecting contiguous to the channelled portions 11, as shown in Fig. 1. It will be noted that one of the channelled portions 11 is struck outwardly to form an outwardly 105 bulged web 19 in diagonal alinement with the lug 18, it being noted that by the forming of the web 19 an opening is formed through one of the channelled portions 11.

When the device is not in use, the side 110

walls of the hood are slipped over the side surfaces of the casing 5 and at this time the disk 16 will extend into the notch 8 of the casing 5, thus causing the hood to fit snugly upon the casing and thus occupy only a minimum amount of space.

When it is desired to use the adjustable lighter, however, it is slipped upwardly and swung around over the upper end of the casing 5 as indicated in Fig. 1, and at this time the hood must be pulled far enough from the casing to allow the channeled portions thereof to extend above the upper end of the casing. At this time the cap 7 may be removed and a match may be extracted from the interior of the casing. The cap may then be again placed upon the casing to prevent accidental displacement of the remaining matches. A cigar or cigarette indicated at 20 may then be inserted into the hood of the adjustable lighter, owing to the channeled construction of the portions 11 until the inner end of the cigar or cigarette is very near to the disk 16. The match 25 21 is then inserted through the opening formed in one of the channeled portions, 11, the movement of the match being guided by the bulged web 19. Continued inward movement of the match will cause the head 30 22 thereof to engage the lug 18 and the periphery of the disk 16, as indicated in Fig. 1. The operator may then quickly revolve the disk 16 by his fingers or thumb thereby causing the friction of the periphery of the 35 disk upon the match head to ignite the match. By having the head bearing upon the lug 18 any possibility of the match being broken is prevented as this lug constitutes a reinforcement for the head. As the 40 match is ignited it is obvious it will ignite the cigar or cigarette end there adjacent. The combustion is supported by allowing the first gases to pass outwardly through the channel formed above the bulged portion as 45 indicated in Figs. 1 and 3.

It will be noted that the device herein described is particularly adapted for use during winds when it is very difficult to ignite a match and then light a cigar or cigarette 50 without the match being accidentally extinguished and furthermore a device of the present nature is adapted for use in trenches or on battle fields where it is not desired to allow the flame of the match to give a signal 55 and indicate the position of the user, owing to the fact that as the flame will be entirely contained within the hood, it will be shielded from view.

Of course under ordinary conditions, such 60 as during the daytime and when there is no wind, the match can be struck upon the milled portion 6 of the casing 5.

It will be noted by the description above given that the device may be used very 65 quickly when desired and may be slipped

to an operative position upon the casing, although when not in use it will fit snugly upon the casing and thus require only a minimum space, since the out-turned edges 13 will facilitate the slipping of the hood 70 over the casing. It will also be noted that the match may be quickly ignited while the position of the bearing lug prevents the match from being broken and the web constitutes a guide for directing the match 75 head into correct position for engagement by the disk and lug.

The foregoing description and the drawings have reference to what may be considered the preferred, or approved, form of 80 my invention. It is to be understood that I may make such changes in construction and arrangement and combination of parts, materials, dimensions, et cetera, as may prove expedient and fall within the scope 85 of the appended claims.

Having thus fully described my invention, what I claim as new and desire to secure by Letters Patent, is:—

1. In a device of the class described, the 90 combination of a hood consisting of a back wall having side walls thereon, means for supporting said hood, a disk carried by said hood, a lug carried by said hood adjacent said disk whereby a match may be placed 95 in engagement with the lug and be ignited by the rotation of said disk.

2. In a device of the class described, the 100 combination of a hood having its side walls longitudinally channeled, a lug formed in said hood adjacent one end thereof, a rotating disk arranged adjacent said lug, one of said channeled sides being struck outwardly to form a bulged web in alinement with said lug, and igniting means carried by said 105 hood adjacent said lug.

3. In a device of the class described, the 110 combination of a hood consisting of a back having side walls, means for supporting said side walls, said side walls being longitudinally channeled, a rotating disk mounted in said hood, a lug formed in said hood adjacent one end thereof, one of said channeled portions being struck outwardly to form a bulged web in alinement with said 115 lug, and igniting means carried by said hood adjacent said lug.

4. In a device of the class described, the 120 combination of a casing, including a notched portion, a hood consisting of a back having parallel side walls provided with out-turned edges, whereby the hood may be slipped onto the casing to be supported, said side walls being longitudinally channeled thus permitting a cigar or cigarette to be slipped 125 into the hood, bearing walls formed at one end of said side walls, said bearing wall having a slot, a disk rotatably mounted upon said bearing wall and projecting through said slot, a lug formed in said hood 130

adjacent said disk, one of said channeled portions being struck outwardly to form a bulged web in alinement with said lug, whereby said web will direct a match to 5 allow the head of the match to bear upon said lug and be engaged by the periphery of the disk, and said hood being slipped onto said casing to allow the disk to fit

within the notch of the casing when the device is not in use. 10

In testimony whereof I affix my signature in presence of two witnesses.

WILLARD A. ELKINS.
